TOILET BOWL BRUSH HOLDER

Carlo Cesani, Trenton, N. J.

Application November 12, 1953, Serial No. 27,545

Term of patent 7 years

(Cl. D4—3)

To all whom it may concern:

Be it known that I, Carlo Cesani, a citizen of the United States, residing in Trenton, in the county of Mercer and State of New Jersey, have invented a new, original, and ornamental Design for a Toilet Bowl Brush Holder, of which the following is a specification, reference being had to the figures of the accompanying drawing, forming a part hereof.

Fig. 1 is a perspective view of a toilet bowl brush holder embodying my new design;

Fig. 2 is a front elevational view;

Fig. 3 is a side elevational view; and

Fig. 4 is a top plan view thereof.

The dotted line disclosure of a container and brush in Fig. 2 is shown only for purposes of illustration.

I claim:

The ornamental design for a toilet bowl brush holder, as shown and described.
